UNITED STATES PATENT OFFICE.

GEORGE A. METCALF, OF MALDEN, MASSACHUSETTS.

GUARD OR GATE FOR STREET-CARS, &c.

No. 845,880.

Specification of Letters Patent.

Patented March 5, 1907.

Application filed August 28, 1906. Serial No. 332,368.

To all whom it may concern:

Be it known that I, GEORGE A. METCALF, of Malden, in the county of Middlesex and State of Massachusetts, have invented certain new and useful Improvements in Guards or Gates for Street-Cars, &c., of which the following is a specification.

This invention relates to a substantially horizontal elongated guard or gate which is vertically movable to and from its operative position, the guard being in this embodiment of my invention an elongated bar, such as is used on an open street-car having side entrances and exits, the guard being adjustable so as to extend across the exits and prevent passage therethrough and to be moved to the upper portions of the exits to permit passengers to pass under it.

My invention has for its object to provide simple and effective means for supporting a guard or gate of this character in such manner that it can be moved vertically from either position to the other by force applied at a single point on the guard and at either end thereof, the supporting means having provisions for equalizing the height of both ends of the guard, so that when displacing pressure is applied to either end the other end will have a corresponding movement, the guard remaining substantially horizontal under all conditions.

The invention consists in the improvements which I will now proceed to describe and claim.

Of the accompanying drawings, forming a part of this specification, Figure 1 represents a perspective view of a guard and means for supporting the same, embodying my invention. Fig. 2 represents a similar view showing a different embodiment of the invention. Fig. 3 represents a side elevation showing the embodiment of my invention represented in Fig. 1 applied to a street-car. Fig. 4 represents a modification hereinafter referred to.

The same letters of reference indicate the same parts in all the figures.

In the drawings, *a* represents a substantially horizontal gate or guard, the same being here shown as a narrow elongated bar, such as is ordinarily used at the side of an open street-car to obstruct the entrances and exits. The bar is adjustably supported and permitted to move vertically by means embodying my invention, which comprise a pair of independent cords, supports therefor, and cord-engaging members on the guard,

the said means having provisions for equalizing the height of the ends of the guard under all adjustments of which the guard is capable.

In the embodiment of my invention shown in Figs. 1 and 3, *b* and *c* represent the two independent cords. The cord *b* is attached at one end to a fixed support *e*, located above one end of the guard, and at its other end to a fixed support *f*, located below the opposite end of the guard. The cord *c* is attached at one end to a fixed support *g*, located above the guard and immediately over the support *f*, and at its other end to a support *h*, located below the guard and immediately under the support *e*. The guard is provided with cord guiding and deflecting members, whereby the central portions of the cords are caused to extend lengthwise of the guard, the ends of each cord being thus offset from each other. The said members, as here shown, comprise pulleys *i i'*, engaging and deflecting the cord *b*, and pulleys *j j'*, engaging and deflecting the cord *c*, the said pulleys being mounted to rotate loosely on studs *k k*, affixed to the guard. The supports *e f g h* may be studs, bolts, or other suitable members affixed to parts of the car-body above and below the spaces in the sides of the car for the entrance and exit of passengers.

It will be seen that the guard is suspended in the bights or loops of the cords *b* and *c*, which engage the pulleys *j j'*, the said bights supporting both ends of the guard at an equal height and preventing either end from dropping below the other. At the same time independent upward movement of either end of the guard is prevented by the bights of the cords which engage the pulleys *i i'*. When the guard is moved upwardly, the upper stretches of the two cords extending between the pulleys and the supports *e* and *g* are shortened, the lower stretches extending between the pulleys and supports *f* and *h* being correspondingly lengthened. An equal movement is imparted to both ends of the guard, so that the guard always remains substantially horizontal, it being impossible for either end to move up or down independently of the other.

Referring to Fig. 2, *b'* and *c'* represent the two independent cords. The supports for the cords are pulleys *m m' m''*, engaged with the cord *b'*, and pulleys *n n' n''*, engaged with the cord *c'*, the said pulleys being mounted to

rotate on fixed journals or studs secured to the body of the car above and below the guard, the pulleys $m\ m'$ and $n\ n'$ being located above the guard, while the pulleys m^2 and n^2 are located below the guard. The 5 cord-engaging members on the guard are here shown as eyes or staples $o\ o'$ and $p\ p'$, the members o and p being at the upper edge and the members o' and p' at the lower edge 10 of the guard. The pulleys $m\ m'$ and $n\ n'$ deflect the cords and cause the central stretches thereof to extend lengthwise of the guard and above the same. The guard is suspended by the engagement of bights of the cords 15 with the pulleys m and n , so that neither end can drop independently of the other, independent upward movement of either end being prevented by the dependent bights of the cords engaging the pulleys m^2 and n^2 . When 20 the guard is raised, the stretches of the cords extending upwardly from the engaging members o and p are shortened, and the stretches extending downwardly from the members o' and p' are correspondingly lengthened, both 25 ends of the guard being kept at all times at a uniform height.

The chief object of my invention is to enable the guard to be adjusted by power applied to it at any point along its length, so 30 that in the case of a street-car the guard may be raised and lowered by an attendant standing at either end of the guard. Usually a guard of this character of sufficient length to obstruct all the side entrances of a street-car 35 requires the services of two persons, one at each end, to raise and lower them. My improvement enables one attendant to easily raise and lower the guard while standing at either end of it and without necessarily taking 40 the trouble to station himself at the central portion of the guard.

My invention is not limited to use in connection with street-cars and may be used in any desired relation. Various other changes 45 in the arrangement of the essential parts of the guard-supporting means may be made without departing from the spirit of the invention.

In Fig. 3 I show means for locking the 50 guard in its raised position, so that it will not be liable to move downward prematurely. The means here shown comprise a spring-catch r on one of the side uprights of the car and a stud or projection s on the 55 guard. The catch r is preferably formed like the catch for an umbrella-runner, so that the projection s in moving upwardly displaces the catch, which springs out under the projection and engages it to prevent downward movement of the end of the guard on 60 which the projection is located, the equalizing supporting means at the same time preventing the opposite end from dropping. The guard may be released by imparting to 65 it an endwise movement sufficient to with-

draw the projection from the catch, this movement being permitted by the flexibility of the cords. To prevent the guard from being thus moved accidentally, a spring t 70 may be attached to one of the uprights in position to bear on a projection u on the guard and yieldingly prevent endwise movement of the guard in the direction required to disengage the projection s from the catch. An operator by grasping any part of the guard 75 can move it endwise against the pressure of the spring t , and thus disengage the projection s from the catch.

It is obvious that the catch may be located 80 so that one end of the guard will slide over and displace the catch, the latter springing out to engage the lower edge of the guard, as shown in Fig. 4, which also shows the spring t arranged to bear against the opposite end of the guard. The spring t may be omitted, 85 however, and the tension of the cords may be relied upon to hold the guard in engagement with the catch, the guard being movable endwise to a limited extent to release it from the catch and returned to its catch-engaging position by the tension of the cords. The catch r may be rigid, so that the guard in passing by it is displaced endwise by the catch and then returns to position to engage the catch. 90

I claim—

1. In combination, an elongated guard and guard-supporting means, comprising a pair of independent cords, vertically-immovable supports therefor on the car, and cord-engaging members on the guard, the cords 100 extending from said supports to the guard, said means having provisions for transmitting from end to end of the guard, movement imparted to either end, and for equalizing the height of the ends of the guard under all 105 adjustments of which it is capable.

2. In combination, an elongated guard, and guard-supporting means, comprising a pair of independent cords, supports therefor, and cord-engaging members on the guard, the 110 cords having supporting-bights which prevent independent downward movement of the ends of the guard, and holding-down bights which prevent independent upward movement of said ends.

3. In combination, an elongated guard, a pair of cords supporting the same, and supports for said cords, each cord being attached at one end to a support above one end of the guard, and at the other end to a support below the opposite end of the guard, and cord guiding and deflecting members on the guard, whereby the central portions of the cords are caused to extend lengthwise of the guard.

4. In combination, an elongated guard, supporting means comprising flexible cords engaged with the guard, and supports for said cords, the said means having provisions for equalizing the height of the ends of the 130

guard, and means for locking the guard in a raised position, said means being adapted to be rendered inoperative by an endwise movement of the guard.

5. In combination, an elongated guard, supporting means comprising flexible cords engaged with the guard, and supports for said cords, the said means having provisions for equalizing the height of the ends of the guard, and a locking member adapted to engage the guard, the latter being longitudinally movable to disengage it from the catch.
10. In combination, an elongated guard,
6. In combination, an elongated guard,

supporting means comprising flexible cords engaged with the guard, and supports for 15 said cords, the said means having provisions for equalizing the height of the ends of the guard, a locking member adapted to engage the guard, and means for yieldingly holding the guard in engagement with said member. 20

In testimony whereof I have affixed my signature in presence of two witnesses.

GEORGE A. METCALF.
